United States Patent Office.

WALTER SAMUEL WITHERS, OF ATLANTA, GEORGIA.

Letters Patent No. 93,939, dated August 17, 1869.

FIRE-PLACE GRATE.

The Schedule referred to in these Letters Patent and making part of the same.

To all whom it may concern:

Be it known that I, WALTER SAMUEL WITHERS, of Atlanta, in the county of Fulton, and in the State of Georgia, have invented new and useful Improvements in Fire-Grates; and do hereby declare that the following is a full, clear, and exact description thereof, reference being had to the accompanying drawings, and to the letters of reference marked thereon.

The nature of my invention consists in the construction and general arrangement of a "portable grate," in which a large or small fire may be had, to suit the convenience.

In order to enable others skilled in the art to which my invention appertains, to make and use the same, I will now proceed to describe its construction and operation, referring to the annexed drawings, which form a part of this specification, and in which—

Figure 1 is a plan view, and

Figure 2 is a transverse vertical section of my portable grate.

A A represent two standards, of any dimensions desired, between which, and at a suitable point above their lower edges, is placed the bottom grate B, secured to the standards by bolts and screws.

The bottom grate is always the one that burns out first, and I have made this portion separate, so that when it burns out it can be removed, and a new one inserted, without losing the whole grate.

The front portion of the grate C is made in any of the known and usual styles, and also secured to the standards A A by bolts and screws. It is also secured to the bottom B by a bolt and screw passing through ears D D, on their under sides, as shown in fig. 2.

At the rear edges, and on the inner sides of the standards A A, are grooved lugs a and a', and at a

suitable point between said lugs and the front grate C, are other grooved lugs, b b', as shown in fig. 2.

In the grooves on said lugs the back E of the grate is inserted, said back consisting of a plate, with a hole or opening, c, in the centre, near the upper edge, to form a convenient handle to remove the back of the grate.

It will be seen that if the back E is placed perpendicularly down through the lugs a a', a very large fire can be obtained. By placing it in an inclined position through the lugs a and b', the grooves in which are made inclined for that purpose, a smaller fire may be made.

The back E may also be placed, as represented in the drawings, perpendicularly through the lugs b and b', which will make a still smaller fire. It may also be placed in front of the latter lugs, if so desired, thus making a very small grate.

Having thus fully described my invention,

What I claim as new, and desire to secure by Letters Patent, is—

1. The combination of the standards A A, bottom B, and front C, constructed and arranged as described, and connected together, substantially in the manner and for the purposes herein set forth.

2. The combination of the standards A A, having grooved lugs a a' and b b', bottom B, front C, and adjustable back E, all constructed and arranged substantially as and for the purposes herein set forth.

In testimony that I claim the foregoing, I have hereunto set my hand, this 2d day of March, 1869.

WALTER SAMUEL WITHERS.
